UNITED STATES PATENT OFFICE.

OTTO MEISSNER, OF COSWIG, GERMANY.

CARBURETER.

1,103,802.

Specification of Letters Patent.

Patented July 14, 1914.

Application filed October 18, 1912. Serial No. 726,566.

To all whom it may concern:

Be it known that I, OTTO MEISSNER, a subject of the Emperor of Germany, and a resident of Coswig, Saxony, Germany, have invented a certain Improved Carbureter, of which the following is a specification.

The present invention relates to a float-feed carbureter and consists in the various details of construction and combination of parts as hereinafter set forth and claimed, the main object of the invention being to produce a carbureter of simple construction which, by a convenient adjustment of a few interconnected elements, can be instantaneously adapted for more or less volatile liquid fuels.

In the accompanying drawings the invention is illustrated by way of example, Figure 1 representing a vertical section of the apparatus, Fig. 2, a plan of the same partly in section, Fig. 3, a sectional view of the atomizer, and Fig. 4, an elevation of the atomizer at right angles to Fig. 3.

The device consists of a casing in which are formed, side by side, a float chamber 24 and a carbureting chamber 1. The carbureting chamber 1 has at the bottom an inlet 2 and at the top an outlet 3. A valve cone 5 is provided for regulating and interrupting the discharge of explosive mixture, and a cone 4 for regulating the air supply. Both valve cones are connected to a common hollow stem 6 so as to be adjusted simultaneously and uniformly. A coil-spring 7, abutting against the lower part of the casing and against the cone 4, tends to hold the outlet 3 closed.

Within the stem 6 a tube 8 is arranged which carries at its upper end a small cone 9 having its seat in the upper part of the cone 5. Below the cone 9 an aperture 10 is made in the tube 8 which is otherwise closed by the cone. The lower end of the tube 8 projects beyond the end of the stem 6 and is provided with a lateral aperture 11. A nut on the projecting end of the tube 8 is engaged by a lever 12 by means of which the valves can be opened, in opposition to the spring 7, and their position regulated.

The channel which leads to the air inlet is divided by a longitudinal partition into two parts 13 and 14 one of which supplies cold and the other hot air. A damper 45 is fitted transversely in the channel so as to be capable of shutting off either the hot or the cold air stream, or, when in an intermediate posi-

tion, of admitting both in suitable proportions. The position of the damper is controlled, through the medium of a system of levers 44, by the flexible wall 42 of a receptacle 43 containing, in known manner, a liquid having a high coefficient of expansion. This receptacle is fitted in the wall of the chamber 1 so as to assume the temperature of the latter. If such temperature should increase, the consequent expansion of the receptacle will cause the damper 45 to be adjusted so as to admit more cold and less hot air. If a reduction in the temperature takes place the reverse will be the effect. In this manner the temperature of the chamber 1 will be automatically regulated.

An inclined socket 48, at the lower part of the carbureting chamber 1, communicates through a duct 16 with the float chamber 24 below the surface of the liquid. A vaporizing tube 15 bears with its lower end against the bottom of the socket 48, its upper part being supported, at the opposite side, in the upper part of the chamber wall. The tube 15 bears against the chamber wall by means of a shoulder and can be withdrawn from the outside. It is normally fastened in position by means of a screw 17 passed through an extension of the shoulder. The internal diameter of the socket 48 is larger than the external diameter of the tube 15 so that a ring-shaped space, opening into the carbureting chamber 1, is left between the elements. On a level with the orifice of the socket 48, the tube 15 is provided with slots 22. Opposite these slots an atomizer, in the form of a longitudinally grooved plug 20, is arranged within the tube. The grooves of the plug are widened downward so as to admit more or less liquid according to their position relative to the apertures 22. For the adjustment of the plug 20, the latter is connected to a rod 19 which is held by a screw-thread in a shoulder in the upper end of the tube 15 and which projects through the latter so as to allow of being turned from the outside. A lock-nut 18 is fitted on the screw-threaded part of the rod for securing the latter and the plug in an adjusted position.

A float 26 is arranged in the chamber 24 in the usual manner. This float carries a valve cone 27 the seat 28 of which is adjustably held in a socket 30 connected to the top cover 29 of the chamber. The socket 30 is encircled by a sleeve 32 having obliquely or spirally disposed slots 38. Screws 37, se-

cured to the valve seat 28, are passed through the slots 38 and through vertical slots 31 in the socket 30. The effect of this arrangement is that, when the sleeve 32 is turned, 5 the screws 37 will be guided by the slots 38 and 31 and adjusted vertically together with valve seat 28. The sleeve 32 is turned by means of a knob 35 connected to an arm 33 on said sleeve. The arm 33 is resilient and 10 carries a stud 36 which secures the sleeve in adjusted position by engagement with a series of recesses made in the cover 29. A pointer 34 is also provided on the arm so as to indicate on a scale the position of the 15 valve seat. The sleeve 32 is retained on the socket 30 by means of a nut 39.

A sliding wedge 41 is interposed between the receptacle 43 and the lever 44. This wedge is connected by a flexible element 40 20 to the sleeve 32 so that an adjustment of the latter causes a simultaneous adjustment of the wedge and consequently of the damper 45.

A gage tube 47, composed wholly or only partly of glass and fitted with a cock 46, 25 communicates with the lower part of the chamber 24.

The chambers 24 and 1 communicate with one another, above the liquid surface, through an aperture or duct 23, and the 30 chamber 24 communicates with atmosphere through an aperture 25 made in the cover 29.

The *modus operandi* is as follows: The valve seat 28, through which the liquid fuel is fed into the chamber 24, is first adjusted 35 by means of the arm 33 in accordance with the particular fuel to be used, it being raised for heavy and lowered for light fuel. Through the medium of the elements 40, 41 and 44, the damper 45 is at the same time 40 adjusted automatically so as to supply warmer air for a heavy and colder air for light fuel. Before the motor is started, the cock 46 is opened so that the level of the liquid is indicated in the tube 47. When the 45 motor is started an underpressure will be produced in the chamber 1 and communicated through the duct 23 to the chamber 24. The degree of such under-pressure can be ascertained from the tube 47 the liquid 50 column of which is correspondingly reduced, the tube being open at the top. The suction of the motor also causes the liquid to be drawn into the carbureting chamber 1 through the duct 16, the tube 15, the grooves 55 21 and the slots 22. The plug 20, which is also adjusted, by means of the rod 9, to suit the nature of the particular fuel used, atomizes the liquid, which is mixed in due proportions in the chamber 1 with the air coming from the inlet 2, the valves 5 and 2 being adjusted by means of the lever 12 so as to supply more or less liquid to the motor 60 according to requirements.

If the speed of the motor should increase 65 owing to excessive feed of mixture, the con-

sequent reduction of the pressure in the carbureting chamber 1 will again be communicated through the aperture 23 to the chamber 24. Owing to the reduction of the pressure in the chamber 24 less liquid will be 70 fed to the vaporizing chamber, and the speed of the motor will thus be automatically restored to the normal.

When the valve 5 is closed for stopping the motor, the suction of the latter will act 75 on and raise the cone 9, atmospheric air will then be admitted through the tube 8 and the apertures 11 and 10 so as to cool and brake the motor.

The temperature of the air supplied 80 through the inlet 2 is regulated, as previously noticed, by the expansible receptacle 43 through the medium of the levers 44 and the damper 45.

The space around the tube 15 in the socket 85 48 serves to receive the fuel discharged through the apertures 22 after the motor is stopped. At the starting of the motor the liquid thus collected evaporates and facilitates the starting.

Owing to the simple construction of the carbureter it is easily adjusted and conveniently cleaned. The tube 15 can be easily removed for cleaning and for controlling the adjustment of the plug 20.

I claim:

1. A carbureter comprising a float chamber, a carbureting chamber communicating with said float chamber below and above the liquid surface, an inclined slotted tube arranged in said carbureting chamber to receive the liquid from the float chamber, a grooved plug arranged in the slotted part of said tube so as to atomize the liquid, means for introducing hot and cold air into 100 the carbureting chamber, means for adjusting the proportions of hot and cold air automatically, a float in the float chamber, a valve cone carried by the same, an adjustable valve seat for said cone, means for adjusting the position of said valve seat according to the nature of the fuel used, and connections between the adjusting device for the valve seat and the regulating device for the air supply causing the proportions 105 of hot and cold air to be varied when the seat is adjusted.

2. In a float-feed carbureter, a carbureting chamber, means for feeding liquid into said chamber, means for atomizing said liquid, an air inlet at the bottom of the chamber, an outlet for the explosive mixture at the top of the chamber, a valve cone for regulating and closing said outlet, a valve cone for regulating said inlet, 120 a hollow vertical stem holding said cones at a constant distance from one another, means for operating said stem so as to adjust the cones, a tube arranged in said stem and having its lower end in com- 125

munication with the atmosphere, a small valve cone connected to the upper end of the tube and seated in the outlet cone so as to be raised by the suction of the motor 5 when said latter cone is moved into closing position, the tube having air vents adapted to admit atmospheric air to the motor when its cone is thus raised, substantially as and for the purpose set forth.

10 3. In a float-feed carbureter, a vaporizing and mixing chamber, a tube arranged in an inclined position in said chamber so as to receive the liquid from the float chamber, a plug having longitudinal downwardly 15 widening grooves arranged opposite slots within said tube so as to atomize the liquid and discharge the vapor through its grooves and the slots of the tube, the upper end of the tube being closed and secured to the 20 chamber wall so as to allow the tube to be removed from the outside, and a rod in said tube holding the plug and fitted by means of a screw-thread in the closed end of the tube so as to allow of being turned from the 25 outside for adjusting the position of said plug relative to the slots in the tube, substantially as and for the purpose set forth.

4. In a float-feed carbureter, the combination with a carbureting chamber connected 30 by means of a duct with the lower part of the float-chamber and having a socket projecting obliquely from said duct into said carbureting chamber, of a tube arranged in an inclined position in said chamber and 35 having its lower end disposed in said socket so as to receive the liquid from the float-chamber, the socket being wider than the tube so that an annular space is formed between them, the tube having slots disposed 40 opposite the orifice of the socket, a plug, having longitudinal downwardly widening grooves, arranged within the tube opposite said slots so as to atomize the liquid and discharge the vapor through its grooves and 45 through the slots in the tube, the upper end of the tube being closed and secured to the chamber wall so as to allow the tube to be removed from the outside, and a rod in said tube holding the plug and fitted by means 50 of a screw-thread in the closed end of the tube so as to allow of being turned from the outside for adjusting the position of said plug relative to the slots in the tube, substantially as and for the purpose set forth.

55 5. In a float-feed carbureter, a carbureting chamber, a channel admitting air to

said chamber, said channel being divided longitudinally into two parts one supplying hot and the other cold air, a damper arranged in a transverse position in said channel so as to be capable of shutting off either the hot or the cold air stream or admitting both in various proportions, an expansible liquid-receptacle built into the wall of the carbureting chamber so as to assume 60 its temperature, a system of levers controlling the position of the damper and adapted to be acted upon by the receptacle for varying the proportions of hot and cold air as the receptacle expands and contracts, a 65 wedge arranged between the receptacle and the lever system so as to allow of being adjusted for varying the initial position of the damper, an adjustable valve for regulating the admission of liquid to the float 70 chamber to suit the nature of the fuel used, and connections between said valve and the wedge for varying the position of the damper simultaneously with the valve.

6. In a float-feed carbureter, a carbureting chamber, a channel admitting air to said chamber, said channel being divided longitudinally into two parts one supplying hot and the other cold air, a damper arranged in a transverse position in said channel so 80 as to be capable of shutting off either the hot or the cold air stream or admitting both in various proportions, an expansible liquid-receptacle built into the wall of the carbureting chamber so as to assume its temperature, a system of levers controlling the position of the damper and adapted to be 85 acted upon by the receptacle for varying the proportions of hot and cold air as the receptacle expands and contracts, a wedge arranged between the receptacle and the lever system so as to allow of being adjusted for varying the initial position of the damper, a vertically adjustable valve for regulating 90 the admission of the liquid to the float 95 chamber to suit the nature of the fuel, a sleeve controlling the position of said valve and adapted to be rotated for its adjustment, and a flexible element connecting said sleeve with the wedge so that the latter is 100 adjusted and the initial position of the damper varied simultaneously with the adjustment of the valve.

OTTO MEISSNER.
